UNITED STATES PATENT OFFICE.

WILLIAM S. FRIEDLANDER, OF PASSAIC, NEW JERSEY.

DESIGN FOR TEXTILE FABRIC.

SPECIFICATION forming part of Design No. 36,405, dated June 30, 1903.

Application filed April 22, 1903. Serial No. 153,876. Term of patent 7 years.

To all whom it may concern:

Be it known that I, WILLIAM S. FRIEDLANDER, a citizen of the United States, and a resident of Passaic, in the county of Passaic and State of New Jersey, have invented and produced a new, original, and ornamental Design for Textile Fabric, of which the following is a specification, reference being had to the accompanying drawing, forming a part thereof, in which is shown a plan view of a strip of fabric embodying the features of my design.

The design comprises a fabric having thereon the representation of pine branches and

cones on the branches, all arranged as shown in the accompanying drawing.

Having thus described my invention, I claim as new and desire to secure by Letters Patent—

The ornamental design for textile fabric shown.

In testimony whereof I have signed my name to this specification in the presence of two subscribing witnesses.

WILLIAM S. FRIEDLANDER.
